UNITED STATES PATENT OFFICE.

FRANK M. WELCH, OF NEW YORK, N. Y., ASSIGNOR TO ALLING & COMPANY, OF NEWARK, NEW JERSEY.

DESIGN FOR A BROOCH OR SIMILAR ARTICLE.

SPECIFICATION forming part of Design No. 36,582, dated October 13, 1903.

Application filed August 26, 1903. Serial No. 170,877. Term of patent 3½ years.

To all whom it may concern:

Be it known that I, FRANK M. WELCH, a citizen of the United States, residing in the city of New York, county of Kings, and State of New York, have invented a new, original, and ornamental Design for Brooches or Similar Articles, as illustrated in the accompanying drawings.

Figure 1 is a top view of my new and ornamental design for brooches or similar articles, and Fig. 2 is a face view of the same.

What I claim as new, and desire to secure by Letters Patent, is—

The ornamental design for a brooch or similar article as shown.

FRANK M. WELCH.
